UNITED STATES PATENT OFFICE.

CHARLES W. ELBLE, OF PORTERVILLE, CALIFORNIA.

DESIGN FOR A COMBINED CIGARETTE, MATCH, AND ASH RECEPTACLE.

Application filed August 29, 1927. Serial No. 23,244. Term of patent 3½ years.

To all whom it may concern:

Be it known that I, CHARLES W. ELBLE, a citizen of the United States, residing at Porterville, in the county of Tulare and State of California, have invented a new, original, and ornamental Design for a Combined Cigarette, Match, and Ash Receptacle, of which the following is a specification, reference being had to the accompanying drawing, forming part thereof, and in which

Fig. 1 is a perspective view of a combined cigarette, match and ash receptacle with the lid closed, showing my new design, and Fig. 2 is a similar view with the lid open.

I claim:

The ornamental design for a combined cigarette, match and ash receptacle, as shown.

CHARLES W. ELBLE.
